US0D1011821S

(12) **United States Design Patent** (10) Patent No.: **US D1,011,821 S**
(45) Date of Patent: ** Jan. 23, 2024

(54) **COUNTERTOP COOKING APPLIANCE**

(71) Applicant: **WHIRLPOOL CORPORATION**,
Benton Harbor, MI (US)

(72) Inventors: **Megan Cheryl Dado**, Benton Harbor, MI (US); **Edward James Haney**, Baroda, MI (US); **John W. McConnell**, St. Joseph, MI (US); **Mansour Ourasanah**, Chicago, IL (US); **Ryan James Rutter**, St. Joseph, MI (US); **Lesley J. Frakes**, Coloma, MI (US)

(73) Assignee: **WHIRLPOOL CORPORATION**,
Benton Harbor, MI (US)

(**) Term: **15 Years**

(21) Appl. No.: **29/827,142**

(22) Filed: **Feb. 17, 2022**

(51) LOC (14) Cl. **07-02**

(52) U.S. Cl.

(57) **CLAIM**

The ornamental design for a countertop cooking appliance, as shown and described.

DESCRIPTION

FIG. 1 is a perspective view of a countertop cooking appliance according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in even broken line form no part of the claimed design.

1 Claim, 7 Drawing Sheets
